UNITED STATES PATENT OFFICE.

JAMES H. FASSETT, OF NASHUA, AND JOHN E. WARREN, OF GREENFIELD,
NEW HAMPSHIRE.

PENCIL-SHARPENER.

SPECIFICATION forming part of Letters Patent No. 701,027, dated May 27, 1902.

Application filed April 4, 1901. Serial No. 54,376. (No model.)

To all whom it may concern:

Be it known that we, JAMES H. FASSETT, of Nashua, and JOHN E. WARREN, of Greenfield, in the county of Hillsboro and State of New Hampshire, have invented a new and useful Improvement in Pencil-Sharpener, of which the following is a specification, reference being had to the accompanying drawings, in which—

10 Figure 1 is a front elevation of our new pencil-sharpener. Fig. 2 is a plan view of the same. Fig. 3 is a central longitudinal sectional view of the pencil-holding device. Fig. 4 is a sectional view on line A A, Fig. 1; and 15 Fig. 5 is a detail showing a modification hereinafter referred to. Fig. 6 is a sectional view on line B B, Fig. 5.

Our invention relates to improvements in machines for sharpening lead-pencils and for 20 like purposes; and the object of our invention is to provide a machine which gives the wood a drawing cut—that is, a cut along the grain of the wood.

Another object of our invention is to provide a machine in which the cutters may be 25 readily changed, sharpened, or replaced.

A third object of our invention is to provide a simple and efficient means for holding the pencil.

30 A fourth object of our invention is to provide a machine which is of simple, durable, and cheap construction and of great capacity.

In the drawings illustrating the principle of our invention and the best mode in which 35 we have contemplated applying that principle, *a* is the supporting-base, upon which are the standards *b* and *c*. In standard *b* is journaled the shaft *p* of the pinion *d*, that meshes with the gear *e*, the shaft of which is journaled in the standard *c*. Fast upon the same shaft with the gear *e* is the bevel-gear *f*, that meshes with the bevel-gear *g*. The hollow shaft *h* of the bevel-gear *g* is journaled in the standard *i*, which is pivotally secured at *j* to 40 the base *a*, so that the standard *i* may be swung horizontally. The pencil *k* is held within a split sleeve of spring-metal *l*, that passes through the hollow shaft *h*. The nut *m* serves to lock the pencil *k* tightly within 45 the sleeve. The cutter-plate *n* is detachably secured by the screw *o* to the shaft *p*, so that

it rotates therewith. The knives *q* are two-edged, as shown in horizontal section in Fig. 4. When the knives are dulled, the cutter-plate may be reversed, so as to bring a new 55 set of cutting edges into use.

Fig. 5 shows a modification in which the pieces *r*, having file-surfaces, are inserted between the knives *q* near their bases. These file-surfaces serve to grind the lead to a fine 60 point.

The operation of our new pencil-sharpener is as follows: The operator by means of the handle *s* turns the gear *e*, and thereby causes the pinion *d* and the bevel-gear *g* to rotate. 65 The rotation of the gear *g* causes the rotation of the sleeve *l* that is secured to the shaft *h* by the set-screw *t*, Fig. 3, and also causes the rotation of the pencil *k*, which is held in the sleeve *l* by the resiliency thereof and by the 70 nut *m*. The rotation of pinion *d* causes the rotation of the cutter-plate *n*, secured to the shaft *p* by the screw *o*. The standard *i* being pivotally mounted at *j* on the base, the pencil is thrown into and out of contact with the 75 knives *q* by rotating the standard *i* on its vertical pivot *j*. The ratio of the gearing is such that the number of revolutions of the cutter-plate *n* is many times that of the pencil *k*, and the number of knives *q* on the plate *n* 80 being large it results that the number of cuts made during one rotation of the pencil is very large. Hence the number of pencils which may be sharpened in a given time or the capacity of the machine is large. Since 85 the knives *q* are two-edged, a simple reversal of the cutter-plate *n* will present a new set of cutting edges. Since the cutter-plate is detachably secured, it may be removed and the knives sharpened, a new or resharpened cutter-plate being substituted for the one dulled. 90

Machines of this class are generally used by office help, school-teachers, pupils, and others little accustomed to mechanical devices. Therefore it is essential that the machines should be simple in construction, not liable to get out of order, and easily repaired and adjusted. These requisites our machine meets completely.

What we claim is—

1. A pencil-sharpener comprising a supporting-frame, mechanism for holding the

100

pencil, a rotary cutter-plate having two-edged knives projecting radially therefrom and adapted to make a drawing cut along the pencil, said cutter-plate being detachably and reversibly secured to a shaft, and mechanism for rotating the cutter-plate.

2. A pencil-sharpener comprising a supporting-frame, mechanism for holding the pencil, a rotary cutter-plate having two-edged knives projecting radially therefrom, said cutter-plate being detachably and reversibly secured to its shaft, and mechanism for rotating the cutter-plate.

3. A pencil-sharpener comprising a supporting-frame, mechanism for holding the pencil, a rotary cutter-plate having knives projecting radially therefrom, members with file-surfaces between said knives, and means for rotating the cutter-plate.

4. A pencil-sharpener comprising a supporting-frame; mechanism for holding the pencil; a rotary cutter-plate having knives projecting radially therefrom and adapted to make a drawing cut along the pencil; members with file-surfaces between said knives; and means for rotating the cutter-plate.

5. A pencil-sharpener comprising a supporting-frame; a pinion; a cutter-plate secured to the shaft of said pinion; a driving-gear that meshes with said pinion; said gear having a shaft; a standard; a rotary pencil-holder in said standard; and a pair of inter-

meshing bevel-gears, one fast upon the shaft of said driving-gear and the other fast to said rotary pencil-holder.

6. In a pencil-sharpener, a device for holding the pencil comprising a spring-metal sleeve having a yielding annular projection on its interior for securing the pencil near one end, and having its other end tapered and slotted and provided with screw-threads on its exterior, and a locking-nut which secures said screw-threaded end to secure the pencil at said end.

7. In a pencil-sharpener, the combination of a supporting-frame; a driving-shaft rotatively mounted therein; a cutter provided with radially-projecting arms sharpened at both their edges and reversibly mounted on said driving-shaft; means for detachably securing said cutter to said driving-shaft; a pencil-holder mounted on said supporting-frame; and means for revolving a pencil in cutting contact with said cutter.

In testimony whereof we have hereunto set our hands, in the presence of two subscribing witnesses, at Nashua, county of Hillsboro, State of New Hampshire, this 19th day of March, A. D. 1901.

JAMES H. FASSETT.
JOHN E. WARREN.
